CLAIM

The ornamental design for a bottle, as shown and described.

DESCRIPTION

FIG. 1 is a perspective view from above and to the right of the bottle embodying the ornamental design;

FIG. 2 is a perspective view from below and to the right of the bottle;

FIG. 3 is a front elevation view of the bottle;

FIG. 4 is a right side elevation of the bottle;

FIG. 5 is a left side elevation of the bottle;

FIG. 6 is a back elevation of the bottle;

FIG. 7 is a top view of the bottle; and,

FIG. 8 is a bottom view of the bottle.

The broken lines in the drawings showing the bottom surface of the bottle illustrates the portion of the design that forms no part of the claim thereof.
